UNITED STATES PATENT OFFICE.

WARREN C. DRAKE, OF INWOOD, NEW YORK.

FURNACE.

Application filed June 25, 1920. Serial No. 391,805.

To all whom it may concern:

Be it known that I, WARREN C. DRAKE, a citizen of the United States, residing at Inwood, in the county of Nassau and State of New York, have invented certain new and useful Improvements in Furnaces, of which the following is a specification, reference being had therein to the accompanying drawing.

This invention relates to furnaces and more particularly to furnaces wherein the fuel support or grate cooperates with furnace walls having perforations or apertures for the injection or admission of air to the combustion chamber. In my prior application Serial No. 242,585, filed June 29, 1918, I show such a furnace in which the walls are provided with apertures arranged to conduct air, supplied under pressure, directly into the fuel bed for the purpose of minimizing the formation of clinkers at the furnace walls and the adherence of such clinkers to the walls, and the difficulties of control and loss of efficiency resulting therefrom. In said prior application, the walls are built up of elements or blocks arranged solidly in face contact and having straight interior apertures or perforations through the body of each block for the admission of air, and lugs formed integrally at the rear of each block to space the same from the outer sides of the furnace to provide passages for the access of air to the apertures leading into the combustion chamber. In these respects and in that the straight apertures terminate flush with the inner face of the furnace wall, the prior structure is disadvantageous, and the main object of the present invention is to provide a different and improved construction of furnace wall or block for non-clinkering or analogous purposes. The nature of the present improvement and the further objects and advantages thereof will be explained in the hereinafter following detailed description of one or more embodiments, or will be apparent to those skilled in the art.

To the accomplishment of such objects and advantages the present invention consists in the novel furnace, furnace wall, wall element or brick, and the features of construction, arrangement, combination, and detail herein illustrated or described.

In the accompanying drawings forming a part hereof, Figure 1 may be considered a vertical longitudinal section taken substan-

tially on the line 1—1 of Fig. 2, and showing a furnace of the underfeed type with inclined grate, and embodying the features of the present invention.

Figure 2 is a plan view taken partly in horizontal section on the line 2—2 of Fig. 1, the exterior elements shown in top view, and the fuel infeeding mechanism being shown only in part.

Figure 3, in plan view, shows blocks in which square recesses are produced for the reception of a separate spacing element or brick arranged to effect a registering or interlocking of adjoining blocks and to stand out rearwardly to space the perforated furnace wall from the outer side wall.

Figure 4 is a side elevation of blocks of the form shown in Fig. 3.

Figure 5, in face or interior elevation, shows a modification in which the separate spacing element or brick is shaped to give a dovetail engagement with and thus interlock two adjoining blocks.

Figure 6 is a side elevation of blocks constructed as in Fig. 5.

Figure 7, in interior or face elevation, shows a modified wall construction wherein the air apertures are provided by grooves at the edges instead of through the interior of the blocks, each groove in one block, for example, registering with a similar groove in the adjacent block to afford a circular aperture.

Figure 8 is a vertical section taken on the crooked line 12—12 of Fig. 7.

The furnace may be of various types, for example the underfeed type, in which a hopper 1 is provided from which fuel is forcibly fed into a retort 2 by means of reciprocating rams 3 operating in casings 4 or boxes located beneath the hopper. The rams are actuated by connecting rods 5, driven from a crank shaft 6 which is revolved in a slow manner by a worm wheel 7 actuated from a worm on drive shaft 8. The infed fuel rests upon the fuel support or grate formed by tuyere boxes 9, or otherwise constituted. The outline of the fuel bed is indicated at 10. Air of combustion may be supplied to the furnace beneath the tuyeres by means of a main air pipe or duct 11, from which a duct 12 is shown extending to the lower part of the furnace. The general form of the grate and the fuel bed is inclined toward the rear of

the furnace, and at the foot of the incline is a grate section 13 upon which the burning fuel passes before it reaches the dumping grate 14, by which, in well known manner, 5 the clinkers and ashes are periodically discharged.

The combustion space or chamber above the furnace grate may be considered as bounded by the furnace front wall 15, the 10 opposite side walls 16, and the rear or bridge wall 17, over which pass the products of combustion; and parts of a boiler 18 are indicated in suitable relation to the described parts.

15 In order to supply air through the furnace walls for non-clinkering or other purposes, I have shown the walls constructed with special furnace blocks or wall elements 19, which may take different forms but are 20 constructed to stand solidly in mutual contact at all sides and yet to provide perforations or apertures for the inwardly directed supply of air. The wall surface constituted by the special blocks 19 is shown as flush 25 with the general surface of each wall. The four walls may be of refractory material, and each of them is indicated as being chamfered or cut away at the interior side to accommodate the special blocks 19 and yet 30 to leave spaces or passages at the rear of the blocks for the flow of the air which is to be supplied through such part of the wall to the furnace interior.

The perforations or apertures 20 are 35 shown as tapered or converging inwardly so as to give the effect of a nozzle or orifice, by which the air, under pressure, may be directed more forcibly into the fuel bed. This feature is of substantial importance as an 40 improvement over said prior application, and it is found to greatly enhance the efficiency of the invention.

The special blocks 19, shown in Figs. 1 and 2, are separately illustrated in different 45 forms in the other figures, for example at 19^b in Figs. 3 and 4. It will here be seen that at the interior side or face the perforations 20 are of much smaller dimension than at the rear, thus giving the tapering and 50 nozzle effect described.

These figures also illustrate another feature of practical importance and value, namely the provision of one or more recesses or depressions 21 at the face of the block adjacent to the orifices. By this means each 55 exit or orifice is inset or depressed below the surface of the block. The formation of clinkers and attachment to the side wall cannot always be wholly prevented, and without 60 the depressions referred to a clinker or other material is apt to become attached or otherwise block up the orifices and thus impair the efficiency of the invention. This improvement wholly obviates the difficulty 65 referred to, and clinkers and fuel are effec-

tively prevented from stopping up the air exits. The depression adjacent each exit may be in the form of a shallow channel, and indeed it is advantageous to have the depression 21 surrounding two different orifices interconnected by narrow depressions 70 22, which, in some cases will give greater efficiency by better distributing the inflowing air.

The body of the blocks should be spaced 75 away from the exterior portion of the walls 15, 16 and 17. Figs. 1-4 hereof show, for this purpose, each block provided with one or more outstanding lugs 23 acting as spacers for the purpose mentioned, the same 80 taking different forms, as 28 and 29, in the other figures.

The air spaces or passages 24 between the special blocks 19 and the outer walls give 85 free air communication, and conduits 25 are indicated leading from the main air duct 11 to these rear passages 24, so that air under pressure is caused to pass into the combustion chamber through the tapered 90 apertures 20. A damper 26 is indicated for 95 the conduit 25 to permit regulation of the air pressure.

Each of the special blocks 19 or 19^b at its rear is formed with a recess 27 to receive 100 a separate spacing element 28 and, as indicated in Figs. 3 and 4, this spacing element or brick 28 engages the recesses 27 of two adjacent blocks so as not merely to perform the function stated but also to register 105 the adjacent blocks with each other and insure a more rigid and permanent furnace wall.

In the modification of Figs. 5 and 6 the blocks 19^c are differently recessed, as shown 105 at 29, so as to receive spacing bricks or blocks 30 of the special form shown, giving a dovetail or interlocking engagement between the blocks 19^c and elements 30.

It is not necessary that the special blocks 19, etc., should be provided with interior 110 apertures or perforations, that is, through the body of the blocks, to supply air to the combustion chamber, as this may be done by means of channels or grooves at the edges of the blocks. Thus, as indicated in Figs. 115 7 and 8, each block 19^d is shown as having a channel or groove 31 at its left edge, a similar groove 32 at its right edge, a similar groove 33 at its top edge, and a similar groove 34 at its bottom edge. These may be arranged so that the grooves in one block will register, as shown, with those in the next block, thus affording round apertures or perforations in the wall. These various 120 grooves, channels, or apertures, moreover, are shown as tapered to give the advantages described in connection with the other figures. Moreover, as in the earlier figures, each aperture or orifice is inset below the 125 face of the block by reason of a shallow 130

depression, for example in the form indicated at 35 for the apertures 31-32, or the form indicated at 36 for the apertures 33-34.

5 Certain features of novelty are not herein claimed but are claimed in a copending application which has now resulted in U. S. Patent 1,400,036 granted December 13, 1921.

It will thus be seen that I have described 10 a furnace and one or more forms of furnace wall and wall blocks embodying the principles and attaining the advantages of the present invention. Since various matters of combination, arrangement, design, and detail may be modified without departing 15 from the principles involved, it is not intended to limit the present invention to such matters, except so far as specified in the appended claims.

20 What is claimed is:

1. A non-clinkering furnace wall comprising inner and outer portions, the inner wall built up of refractory blocks constructed to afford air apertures directed into the fuel bed, such block presenting rear recesses 25 adapted to receive separate spacing members, and separate spacing members engaged in such recesses of the inner wall so as to be supported thereby and to project rearwardly and contact the outer wall, to hold the walls 30 spaced apart and maintain pas-

sages for conducting air to said apertures.

2. A furnace wall as in claim 1 and where-
in adjacent wall blocks are recessed in regis-
ter, and a single spacing member engages 35
such recesses acting to position the blocks
in register.

3. A furnace wall as in claim 1 and where-
in adjacent wall blocks are recessed in regis-
ter, and a single spacing member engages 40
such recesses acting to position the blocks
in register and the recesses and spacing
member being shaped to give interlocking
between adjacent blocks.

4. A non-clinkering furnace wall compris-
ing inner and outer portions, the inner wall
built up of refractory blocks, adjacent
blocks constructed with registering edge
grooves to afford air apertures directed into
the fuel bed, and such adjacent blocks pre-
senting registering rear recesses, and a sepa-
rate spacing member engaged in such regis-
tering recesses of the inner wall so as to be
supported thereby and to project rearwardly
and contact the outer wall, to hold the walls 50
spaced apart and maintain passages for con-
ducting air to said apertures, while ensur-
ing the registration of the grooves forming
such apertures.

In testimony whereof, I have affixed my
signature hereto.

WARREN C. DRAKE.
